US0D1031995S

(12) **United States Design Patent** (10) **Patent No.:** **US D1,031,995 S**
(45) **Date of Patent:** **** Jun. 18, 2024**

(54) **DIAGNOSTIC APPARATUS**

(71) Applicant: **bioMérieux**, Marcy l'Etoile (FR)
(72) Inventors: **Cyril Mézière**, Villeurbanne (FR);
Philippe Marbaix, La
Balme-les-Grottes (FR); **Enrico Balatri**,
Florence (IT)

(73) Assignee: **bioMérieux**, Marcy l'Etoile (FR)

(**) Term: **15 Years**

(21) Appl. No.: **29/809,071**

(22) Filed: **Sep. 24, 2021**

(30) **Foreign Application Priority Data**

Mar. 26, 2021 (EM) 008475636-0001
Mar. 31, 2021 (EM) 008481923-0001

(57) **CLAIM**

The ornamental design for a diagnostic apparatus, as shown and described.

DESCRIPTION

The patent or application file contains at least one drawing executed in color. Copies of this patent or patent application publication with color drawings will be provided by the Office upon request and payment of the necessary fee.

FIG. 1 is a front perspective view of the diagnostic apparatus according to our design;

FIG. 2 is a rear perspective view thereof;

FIG. 3 is a front view thereof;

FIG. 4 is a rear view thereof;

FIG. 5 is a bottom view thereof;

FIG. 6 is a top view thereof;

FIG. 7 is a bottom perspective view thereof; and,

FIG. 8 is a right-side view thereof, the left-side view being a mirror image thereof.

**1 Claim, 8 Drawing Sheets
(8 of 8 Drawing Sheet(s) Filed in Color)**
